UNITED STATES PATENT OFFICE

HENRY P. TYLER, OF SPRINGFIELD, MASS., ASSIGNOR OF THREE-FOURTHS
TO ANDREW TITUS AND SARAH A. ATWOOD, BOTH OF SAME PLACE.

MOP-HEAD.

SPECIFICATION forming part of Letters Patent No. 269,746, dated December 26, 1882.

Application filed May 25, 1882. (No model.)

To all whom it may concern:

Be it known that I, HENRY P. TYLER, a citizen of the United States, residing at Springfield, in the county of Hampden and State of

5 Massachusetts, have invented new and useful Improvements in Mop-Heads, of which the following is a specification.

This invention consists in the combination, with a peculiarly-constructed mop-head, of a 10 spring-binder in one piece of wire formed to inclose the head, and, by having its spring ends bear on the rear of the head, clamp the cloth between its front part or face and the wire. The rear of the head is provided with 15 depressions to hold the ends of the binder, and its outside ends with channels or other similar means of guiding the movement of the binder relative to the face of the head, and preventing its displacement from the head.

20 In the drawings, Figure I is a side view of my improvement in mop-heads. Fig. II is a side view of the binder, and Fig. III is a view of the back of the head.

B is the binder, of continuous wire, formed 25 into loops upon each side of the handle C to present springs acting through the ends b b at approximately right angles to the part h.

D is the head proper, attached to the handle C in any well-known way, and having in its 30 ends the channels d d.

ff are sockets in the back of head D, to receive the spring ends b b of binder B. The sockets f f are open at the top to permit the ends b b to be easily inserted or withdrawn, 35 but deep enough to through their side walls prevent these ends from being displaced through any movement of the mop.

In Fig. II the binder B is shown as having the spring-loops start outward from the points 40 a a, leaving the intermediate portions of the

wire to form in effect a straight bar, h, with shoulders h' h' at right angles thereto, and conforming to the face of the head and its two ends.

In uniting binder and head the spring ends 45 of the loops are pressed aside by the head D until the channels d d and shoulders of the binder at a a are in a prolongation, when the head is slid upon the binder to inclose the cloth or other material forming the mop between the 50 face of the head and the part h of the binder. The spring ends b b are then sprung into position, as shown in Fig. I, in the sockets ff, to firmly bind the mop.

The face of the head D is grooved, as indicated in dotted lines, Fig. I, to afford a larger clamp-surface to the binder than a flat face would, and also to assist in holding binder and head together.

The bearing ends b b of the binder are turned 55 in, as seen in Fig. II, to form, with the rest of the loops, continuous surfaces leading to the mop-bearing portion h, and thus offer no obstacle against which the cloth can catch in placing it.

By these means a strong and easily-operated 60 mop-head is formed in only two parts.

Now, having described my invention, what I 65 claim is—

The improved mop-head, consisting of the 70 binder B, of one piece of spring wire, formed to inclose the head D and bear upon all of its sides in the same plane, in combination with the head D, provided with the end guides or channels, d d, and sockets ff, substantially as 75 and for the purpose shown and described.

HENRY P. TYLER.
